CHARLES A. RIGHTER.

UNITED STATES PATENT OFFICE.

CHARLES A. RIGHTER, OF PHILADELPHIA, PENNSYLVANIA, ASSIGNOR TO
JAS. & GEO. D. BROMLEY, OF SAME PLACE.

DESIGN FOR A CARPET.

SPECIFICATION forming part of Design No. 13,167, dated August 8, 1882.

Application filed June 26, 1882. Term of patent 3½ years.

To all whom it may concern:

Be it known that I, CHARLES A. RIGHTER, of the city of Philadelphia, county of Philadelphia, State of Pennsylvania, have invented and produced a new and original Design for a Carpet, of which the following is a specification.

The nature of my design is fully represented in the accompanying photographic illustration, to which reference is made.

I claim as my invention as follows:
The design for a carpet, as herein shown and described.

CHARLES A. RIGHTER.

Witnesses:

JOSEPH MERCER,
GEO. H. MERCER.
